(57) **CLAIM**

The ornamental design for a motorcycle handlebar as shown and described.

DESCRIPTION

FIG. 1 is a perspective view of a motorcycle handlebar embodying my new design;

FIG. 2 is a left side elevation view thereof, the right side elevation view is a mirror image thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is FIG. 1 rotated 90 degrees counter-clockwise thereof; and,

FIG. 8 is FIG. 2 rotated 90 degrees counter-clockwise thereof.

The broken lines in the drawings illustrate portions of the motorcycle handlebar that form no part of the claimed design.

1 Claim, 4 Drawing Sheets
